CLAIM

The ornamental design for a handheld information and collection device with cradle, as shown and described.

DESCRIPTION

FIG. 1 is a front view of a handheld information and collection device with cradle showing my new design wherein the handheld device is shown separately for clarity of illustration only;

FIG. 2 is a right side view thereof;

FIG. 3 is a back view thereof;

FIG. 4 is a left side view thereof;

FIG. 5 is a top view thereof;

FIG. 6 is a bottom view thereof;

FIG. 7 is a front view of the cradle thereof shown separately for clarity of illustration only;

FIG. 8 is a right side view thereof;

FIG. 9 is a back view thereof;

FIG. 10 is a left side view thereof;

FIG. 11 is a bottom plan view thereof; and,

FIG. 12 is a perspective view thereof wherein the handheld device is shown mounted to the cradle.
